UNITED STATES PATENT OFFICE.

CLARENCE P. ELLITHORPE, OF CHICAGO, ILLINOIS.

AIRSHIP.

Application filed February 16, 1925. Serial No. 9,435.

To all whom it may concern:

Be it known that I, CLARENCE P. ELLITHORPE, a citizen of the United States, and a resident of the city of Chicago, county of Cook, and State of Illinois, have invented 5 certain new and useful Improvements in Airships, of which the following is a specification.

My invention pertains to an airship, and 10 its primary object is to provide a novel device of this character which is simple and durable in construction, efficient in use and economical in manufacture. Another object is to equip such a device with casing means 15 which provides one or more air passages or channels extending longitudinally through the airship, and to place a propeller in each of said passages, each propeller being mounted directly on the shaft of its driving 20 motor likewise mounted within the passage.

Other objects will appear hereinafter.

The invention consists in the combinations and arrangements of parts hereinafter described and claimed.

25 The invention will be best understood by reference to the accompanying drawings forming a part of this specification, and in which,

Fig. 1 is a vertical sectional view of my 30 invention;

Fig. 2 is a horizontal sectional view thereof;

Fig. 3 is an enlarged front elevation thereof;

35 Fig. 4 is an enlarged vertical cross section taken on line 4—4 of Fig. 1; and

Fig. 5 is an enlarged horizontal sectional view of the rear portion of my invention.

The particular form of invention illustrated 40 comprises a main frame 10, preferably of aluminum, with a casing or channel member 11 extending longitudinally therethrough and forming a continuous air passage, but two or more such casings 11 may be used and grouped or placed in any suitable manner within the main frame, and they may be of any approved form in cross section. The main frame includes cross partitions 12 and longitudinal partitions 13, 45 and gas bags 14 are mounted therebetween, thus providing a plurality of separate and independent gas chambers 15. A meshed guard member 16 is mounted across the front opening of the casing or channel member 11.

A motor or engine 17, preferably a powerful gasoline engine, of any approved construction, is mounted centrally in the casing, preferably by means of frame members or bars 18, and has a propeller 19 mounted on 60 bars 18, and is rotatable with the motor shaft 20 which extends longitudinally of the casing. By thus mounting the propeller directly on the motor shaft, the use and weight of the customary additional supporting frame for the 65 propeller is avoided.

The rudder supporting means includes a frame structure 21 mounted to the rear of the main frame and containing horizontal cross shafts 22 and 23 extending diametrically across the casing 11, and outer longitudinal bars 24 extending forwardly from shafts 22 and 23 to the main frame, as at 25. Horizontal stabilizers or fins 26 are mounted on the frame 21, forwardly of said cross 75 shaft 22, and a horizontal rudder 27 is mounted on shaft 23 with an upper arm 28 and a lower arm 29 to which cables 30 and 31 are connected respectively for swinging said rudder on the shaft 23, so as to extend 80 it at a slant across the rear of the casing or channel member. Said cables 30 and 31 pass over pulleys 32 and 33 mounted on arms 34 and 35 extending from across shaft 22 and from a longitudinal strengthening bar 36 85 which extends to the rear of rudder 27 and to shaft 23. The cables 30 and 31 continue from pulleys 32 and 33 forwardly over pairs of successive pulleys 37, 38 and 39, mounted 90 within the casing, and from there pass over additional pulleys 40 on the main frame, as shown, and are attached to a drum or suitable operating element 41 in the cabin 42 which is mounted beneath the airship in any 95 suitable manner. A vertical rudder 44 is mounted on a shaft 45 positioned diametrically at the rear of casing 11 and is provided with arms 46 and 47 from which extend cables 48 and 49 passing over successive 100 pairs of pulleys 50, 51 and 52 mounted in casing 11, and therefrom said cables pass over pulleys 53 provided on the frame, as indicated in the drawings, to a drum 54, or similar operating means, provided in cabin 105 42. Vertical stabilizers or fins 43 are mounted at the rear of the frame, similar to horizontal fins 26, extending forwardly of rudder 44. A shaft 55 is provided, and extends from an opening 56 in casing 11, adjacent the motor or engine 17, through the 110

top of the cabin 42, and is equipped with a ladder 57, to provide access from the cabin to the casing and the motor and propeller therein, this shaft 55 being preferably constructed of cloth or pliable material and the ladder being preferably of rope. An anchor 58 is preferably also provided and mounted on a cable 59 passing over pulleys 60 and 61 into the cabin to be attached to a drum or suitable operating means 62 in the cabin.

10 A water container or tank 63 is mounted in the lower part of the main frame, and a gasoline container or tank 64 is preferably mounted on the cabin or beneath the main frame, and a conduit 65 extends therefrom to the engine 17. A parachute 66 is also provided and preferably mounted as shown.

15 A dirigible airship embodying my invention is particularly efficient, as the propeller is mounted directly on the motor shaft, to avoid the intermediate gearings and additional mounting means for the propeller, and especially as the propeller operates in the compressed stream of air forced through 20 the casing or tube 11, thus being particularly effective in propelling the airship. The casing or air tubes may be made round or angular or in any approved shape, and several 25 of the casings or tubes may be used instead of the one tube as shown; and furthermore this form of construction is not only useful 30 for passenger carrying airships, but will also find application and be produced in the form of toy balloons or airships, and 35 find application in various similar ways.

20 While I have illustrated and described the preferred form of construction for carrying my invention into effect, this is capable of variation and modification without departing from the spirit of the invention. I, therefore, do not wish to be limited to the precise details of construction set forth, but desire to avail myself of such variations and modifications as come within the scope 40 of the appended claims.

25 Having described my invention, what I claim as new and desire to secure by Letters Patent is:

30 1. An airship having a casing extending longitudinally therethrough, a propeller with a motor therethrough mounted in said casing, a plurality of separate gas compartments arranged around said casing, and a water container in the lower ones of said 35 compartments.

35 2. An airship having a casing extending longitudinally therethrough, a propeller with a driving motor mounted in said casing, gas compartments arranged around said 40 casing, a cabin beneath said compartments, and a shaft of pliable material with a ladder extending from said cabin through one compartment into said casing adjacent said motor.

45 3. An airship having a casing extending

longitudinally therethrough, a frame including a pivot shaft mounted horizontally to the rear of said casing, a horizontal rudder mounted forwardly on said shaft to extend diametrically of said casing, cable guiding means on said frame, arms on said shaft, and cable means connected to said arms and traveling over said guiding means for swinging said rudder to tilt or slant across the rear of said casing.

4. An airship having a casing extending longitudinally therethrough, gas compartments around said casing, a cabin mounted underneath said airship, stabilizers at the rear portion of said airship, a pivot shaft 70 mounted rearward of said stabilizers, a horizontal rudder mounted to swing on said shaft and extending therethrough forwardly toward said stabilizers, and cable means extending to said cabin for swinging said 75 rudder.

5. An airship having a casing extending longitudinally therethrough, a supporting frame including a vertical shaft at the rear of said casing, a vertical rudder mounted 80 on said shaft, a horizontal shaft mounted rearward of said vertical shaft, a horizontal rudder mounted forwardly of and to swing on said horizontal shaft, and means for extending said rudders at a slant across the 85 rear of said casing.

6. An airship having a casing extending longitudinally therethrough, a propeller within said casing, a motor in said casing 90 for driving said propeller, a cabin mounted underneath said airship, a passage from said cabin to said casing adjacent said motor, vertical and longitudinal rudders at the rear of said casing, and cable means extending to and operable from said cabin 95 for swinging said rudders.

7. An airship having a casing providing a longitudinal air passage through said airship, a supporting frame mounted to the rear of said casing, a horizontal shaft on said supporting frame, a horizontal rudder extending forwardly from said shaft, arms extending from said rudder, arms extending from said supporting frame and having pulleys thereon, and cable means extending from the first arms over said pulleys through said casing for swinging said rudder to extend at a slant to the rear of said casing.

110 8. An airship having a casing providing a longitudinal air passage therethrough, horizontal and vertical stabilizers at the rear of said airship, a horizontal bar mounted rearward of said casing, a horizontal rudder mounted forwardly on said bar to swing vertically therewith, a vertical rudder mounted forwardly of the horizontal rudder, and cable means for swinging said rudders.

115 9. An airship having a casing extending longitudinally therethrough to provide an air passage, gas compartments arranged 120

125

around said casing, a motor mounted centrally in said casing, a propeller on the shaft of said motor, a horizontal rudder mounted to the rear of said casing to extend diametrically of said air passage, means for

5 swinging said rudder at a slant across said air passage, a vertical rudder mounted to

the rear of said casing, and means for swinging said vertical rudder at a slant across said air passage.

10

In testimony whereof, I have signed my name to this specification.

CLARENCE P. ELLITHORPE.
